R. J. WILSON.

FURNACE.

FILED AUG. 30, 1921.

INVENTOR:
Robert J. Wilson
BY
Pierre Barnes
ATTORNEY

UNITED STATES PATENT OFFICE.

ROBERT J. WILSON, OF SEATTLE, WASHINGTON.

FURNACE.

Application filed August 30, 1921. Serial No. 496,826.

To all whom it may concern:

Be it known that I, ROBERT J. WILSON, a citizen of the United States, residing at Seattle, in the county of King and State of Washington, have invented certain new and useful Improvements in Furnaces, of which the following is a specification.

This invention relates to coal burning apparatus.

10 The object of my invention is to provide improved means whereby the fuel may be economically fed to and consumed with a maximum of efficiency.

The invention consists in the novel construction, adaptation and combination of parts hereinafter described and claimed.

In the accompanying drawings,—

Figure 1 is a longitudinal vertical section taken substantially through broken line 1—1 of Fig. 3. Fig. 2 is a sectional plan view through broken line 2—2 of Fig. 1. Fig. 3 is a transverse sectional view through line 3—3 of Fig. 2, parts to the right of line 3—3 being omitted. Fig. 4 is a detail sectional view of the rotary scraper shown detached, said section being taken on broken line 4—4 of Fig. 2.

Referring to the drawings, the numeral 5 represents a circular plate having a central opening 6 and a plurality of slots 7 and constitutes the grate member of my burner.

Extending upwardly about the periphery of the grate 5 is a circular wall 8.

Below the grate and rigidly connected therewith is a casing 9 containing a cylindrical chamber 10 of approximately the internal diameter of the wall 8.

The chamber floor 11 is provided with a central circular opening 12 of approximately 40 the diameter of the grate opening 6 and is connected by an elbow passage 13 with a horizontal conduit 14 leading from the outlet 15 of a fuel hopper 16.

Provided within the conduit 14 is one or 45 more helical conveyors 17, two being shown, whereby coal or other suitable fuel is transferred from the hopper 16 through conduit 14 and elbow passage 13, the curved end 18 of the latter serving to direct the fuel upwardly through the floor and grate openings 12 and 6 onto the grate 5.

In being elevated to the grate, the fuel is guided by means of a ring 20 which constitutes the hollow hub of a wheel or scraper 55 which is adapted to rotate in the direction of arrow A in Fig. 2. Said wheel has a

rim 21 which is connected by spokes 22 with the hub 20.

Each of said spokes is in the nature of a scraper blade and has its leading edge 23, 60 as shown in Fig. 2, curved forwardly with reference to its direction of travel for the purpose of progressively scraping the floor of cinders or ashes and conveying the same through ways 19 provided beneath the hub 65 to be elevated with the fuel feed onto the grate.

Carried by the scraper hub 20 is an attachment provided with a shank 26 which extends upwardly through the grate opening 6 and thence extends as a plow 27 over the grate in a substantially radial direction with respect to the grate axis.

The underside of the plow 27 is plane and its upper surface 28 is curved, as shown, 75 whereby the plow in its orbital travel acts to progressively elevate the fire bed from the grate.

29 represents a motor driving a shaft 30 upon which is mounted a worm 31 which 80 serves to rotate a worm wheel 32 mounted on a second shaft 33.

This second shaft, in turn, drives through the medium of a spur pinion 34 and a gear wheel 35, a third shaft 36 which latter has 85 mounted thereon within the chamber 10 a toothed pinion 37 engaging teeth 38 provided in the underside of the scraper rim 21 to effect the rotation of the scraper.

As illustrated in Figs. 1 and 2, the shaft 90 36 is utilized to drive the conveyors 17 through the medium of gear wheels 36' and 17'.

Air for combustion purposes is supplied into the chamber 10 by a duct 39 leading 95 from the housing of a fan or blower 40 which is advantageously mounted on the motor driven shaft 30.

41 represents a gate provided in the outlet of the hopper 16 to regulate the delivery 100 of fuel therefrom to the conveyor.

To obviate down-draft through the openings 19, I provide an aperture 42 in the floor 11 to admit air from the chamber 10 into the conduit 14 at a short distance from 105 the floor opening 12.

The plow 28 above the grate 5 is revolved continuously with the scraper during the operation of the burner to loosen or break up the bed of burning coal immediately above 110 the grate for the passage of air from the grate slots 7 thereby producing a hot fire to

effect the combustion of the fuel delivered by the feeding devices over such fire bed.

The plow 28 by its revoluble travel serves to spread the fuel upon the grate, break up 5 the bed of fire and discharge the ashes over the top of the wall 8.

Any ashes falling through the grate slots 7 are swept by the scraper blades 22 into the vertically moving column of fuel to be 10 elevated thereby to above the fire bed on the grate. The air for combustion is supplied under a forced draft into the chamber 10 whence it escapes through the grate slots 7 to the fire.

15 Changes may be made in the details of the invention as herein embodied without departing from the spirit thereof and I accordingly do not confine the invention to the specific embodiments shown except as I may 20 be limited by the appended claims.

What I claim, is—

1. In apparatus of the class described, the combination of a grate having a central feed opening, means for forcing fuel from below 25 through said grate opening, a plow revoluble above the grate, and means to drive the plow.

2. In apparatus of the class described, the combination with a circular grate having a 30 central feed opening, a wall provided about the periphery of said grate, a plow located above the grate, power driven means extending through the grate opening for revolving said plow, and means for forcing fuel from below through said grate opening and cooperating with said plow to deliver the ash products over the top of said wall.

3. In apparatus of the class described, the 40 combination of a grate having a central feed opening, means for feeding fuel from below

through said grate opening, a compressed-air receiving chamber located below the grate, a plow revoluble upon said grate to loosen the fire-bed therefrom for the admission of air through the grate from said chamber. 45

4. In apparatus of the class described, the combination of a grate having a central feed opening and a plurality of apertures in the 50 part of the grate surrounding said opening, a chamber below the grate, an under fuel-feed extending through said chamber, and revoluble means provided in said chamber whereby ashes falling through said grate 55 apertures are conveyed into said fuel-feed.

5. In apparatus of the class described, the combination of a grate having a central feed opening, an elbow passage provided below said opening, power driven devices for feeding fuel upwardly through said elbow passage and the grate opening, and power driven means whereby ashes falling through the grate are conveyed into the fuel-feed above said elbow passage. 65

6. In apparatus of the class described, the combination of a grate, an underfeed therefor, a chamber located below the grate, a rotatable scraper provided in said chamber, 70 said scraper having curved blade elements adapted to convey to said underfeed ashes which fall through the grate, a revoluble plow provided on said grate and operatively connected to said scraper, and means for driving said scraper. 75

Signed at Seattle, Washington, this 23rd day of August, 1921.

ROBERT J. WILSON.
